UNITED STATES PATENT OFFICE.

WENZEL HLAVÁČEK, OF MEISSEN, GERMANY.

SEWING-MACHINE.

SPECIFICATION forming part of Letters Patent No. 645,295, dated March 13, 1900.

Application filed June 7, 1898. Serial No. 682,833. (No model.)

To all whom it may concern:

Be it known that I, WENZEL HLAVÁČEK, a citizen of the Empire of Austria-Hungary, and a resident of Meissen, in the Kingdom of Saxony and German Empire, have invented certain new and useful Improvements in Sewing-Machines, of which the following is a specification.

The object of the present invention is an improvement for reversing the motion of the feeding mechanism of a sewing-machine which permits the changing of the direction of the feeding during the fastest running of the machine.

15 The improvement is shown in the accompanying drawings, wherein—

Figure 1 represents, as seen from below, the invention, showing the parts of the mechanism when the machine feeds forward. Fig. 2 shows the same view, but the parts in their relative position, when feeding backward. Fig. 3 is a cross-section through same on line $x\ x$ of Fig. 1. Fig. 4 is a cross-section on line $y\ y$ of Fig. 2 on an enlarged scale. Fig. 25 5 shows the principal part of Fig. 3 on an enlarged scale.

The vertical axis E, arranged in the vertical arm of the sewing-machine, imparts by means of an eccentric a to-and-fro motion to 30 the feed-dog T through a lever A. The latter is not, as is ordinarily the case, formed by a single solid rod; but it consists of two pieces A and A', connected to each other by an intermediate piece H, articulated at g and 35 g' to A and A'. The piece H is provided with an elongation beyond the pivot g, so as to form a one-armed lever. The same has at one end and between the two pivots g and g' broader parts e and e'. The lever A is prolonged beyond the pivot g and guided in a 40 piece F, fixed to the bed-plate of the machine. F permits only a displacement in longitudinal direction, but prevents that in lateral sense.

45 G is a movable guide-block in which the lever A' is guided, forming thus the fulcrum for said lever. By shifting said piece G to one or the other side the proportion between

the lever-arms is altered, and therefore also the length of the stitches. The reversing of 50 the motion is attained by shifting the bar S by means of the arm h to one side or the other. With this bar S there is rigidly connected a piece S', having near its end a groove engaging with the connecting-piece H. 55

It is obvious that in the position of the parts shown in Fig. 1 the parts A, A', and H behave exactly like one solid piece. The movement of the feeding mechanism therefore takes place in the ordinary way. If, on 60 the other hand, the piece S' is shifted to the left, as shown in Fig. 2, the fulcrum of the connecting-piece is shifted from e to e'. Lever A' therefore executes its motion in opposite sense to lever A, and consequently the 65 feeding mechanism acts in inverse sense.

The reversing device may be attached without much cost to any existing machine of the Singer type.

What I claim is—

1. In combination, the feed mechanism comprising a feed-dog, the vertical shaft, the lever connected to said dog, the lever operated by said shaft, and a link connecting said levers, a fulcrum for said link and means for 75 shifting said fulcrum, substantially as described.

2. In combination, the feed mechanism comprising the feed-dog, the lever connected thereto, the rotatable shaft, a second lever 80 operated by the same, a link having a pivotal connection at one end to the first lever and a pivotal connection to the end of the second lever, an extension of said link to the rear of said second connection, fulcrum-points 85 on said link intermediate of its pivotal connection and on said extension and a shiftable bearing adapted to engage the points between the pivots or said extensions.

In testimony whereof I affix my signature 90 in presence of two witnesses.

WENZEL HLAVÁČEK.
